DOOR HANGER

Leonora R. Martin and Douglas Kline, San Francisco, Calif.

Application February 18, 1947, Serial No. 729,242

8 Claims. (Cl. 211—114)

1

The invention, in general, relates to supporting devices and more particularly relates to an improved hanger especially adapted for removable attachment to doors for increasing closet space.

Some attention has been devoted heretofore to the development of hangers and appliances for attachment to doors for enabling the storing or hanging of an increased number of garments, including hats, shoes and other apparel, as well as for storing a variety of different articles. Many of the devices so developed are somewhat cumbersome not only with respect to construction but also are somewhat difficult to handle and to install. A serious disadvantage of these prior devices resides in the fact that installation thereof causes defacement of doors by screw or nail holes. The present invention is directed to the provision of a relatively simple hanger of inexpensive production which can readily be attached and as readily removed from a door, and which does not in any manner mar the door.

A primary object of the invention is to provide an improved door hanger which affords increased facilities for hanging or storing of a variety of different articles, including clothing, shoes and other items of wearing apparel, and which is readily collapsible for easy shipping and handling.

Another object of our invention is to provide an improved door hanger of the aforementioned character which is readily and easily installed upon a door as well as easily and readily removed therefrom by the unskilled as well as the skilled.

A still further object of our present invention is to provide an improved door hanger of the indicated nature which is especially characterized by its adaptability to be secured in effective operative position without marring or in any way defacing the door upon which it is mounted.

Another object of the invention is to provide an improved door hanger of the aforementioned character which is so constructed as to permit placing an appreciable tension on desirable portions thereof for enabling the hanger to support appreciably heavy loads without likelihood of damaging the same.

Other objects of the invention, together with some of the advantageous features thereof, will appear from the following description of a preferred embodiment of the invention which is illustrated in the accompanying drawings. It is to be understood that we are not to be limited to the precise embodiment shown, nor to the precise arrangement of the various parts thereof, as our

2

invention, as defined in the appended claims, can be embodied in a plurality and variety of forms. Referring to the drawings:

Figure 1 is a front elevational view of a preferred embodiment of the invention installed in operative position on a door.

Figure 2 is an elevational sectional view, taken on the line 2—2 of Figure 1.

Figure 3 is a perspective view of one of the main elements of the preferred embodiment of the invention.

Figure 4 is a perspective view of another of the main elements of the preferred embodiment of the invention.

Figure 5 is a perspective view of a cross-bar forming one of the means for attaching cases, cabinets or the like to a preferred embodiment of the invention.

Figure 6 is a sectional elevational view, in reduced form, illustrating the support of a full length cabinet on our improved hanger in operative position attached to a door.

In its preferred form, the improved door hanger of our invention preferably comprises a cross-bar including clamps for removably fitting the cross-bar to the top edge of a door, a pair of arms secured together at one end and movably mounted on said cross-bar, together with a vertically adjustable rod detachably secured to the connected ends of said arms, a clamp on said rod removably fitting over the lower edge of the door, and a cabinet supporting bar removably mounted on said arms to spread the same and to place the hanger under tension and rigidly fastened to the door.

As particularly illustrated in Figures 1, 3 and 4 of the annexed drawings, our improved door hanger is constructed from three principal elements including a cross-bar 11 which preferably is fabricated from metal but which can be formed of a plastic material or from wood or other suitable strong material. The cross-bar 11 is provided with a pair of clamps 12 and 13 which may be formed integral with the bar or which can be detachably secured thereto, such clamps being located adjacent to opposite lateral extremities of the cross-bar, as clearly shown in Figures 1 and 4. Clamps 12 and 13 conveniently are formed with a depending lip 14 thereon and to a width approximately equal to the width of the top edge of the door upon which the hanger is to be installed so that the cross-bar 11 can readily be hung over the top edge of the door without the necessity of nails, screws or other extraneous fastening means. The cross-bar 11 is formed

with a pair of spaced, elongated slots 16 therein for receiving the upper ends of a pair of arms 17 and 18 which are provided with bolts 19 for passing through the slots 16. The lower ends of the arms 17 and 18 are permanently connected together by means of a bolt 21, and the two mounted arms thus afford a Y-connection with the cross-bar 11 with the arms movable laterally in the slots 16. Preferably, the arms 17 and 18 are fabricated from relatively thin section flat metal, but these arms likewise can be made from wood or from suitable plastic material.

In accordance with our invention, in third principal element of the hanger comprises a flat rod 22 formed with a series of openings 23 therein adjacent to its upper end and carrying a hook clamp 24 on its lower end which is in all respects similar to the clamps 12 and 13 of the cross-bar 11 except that the lip 26 of the clamp 24 is upturned rather than downturned, so as to enable the clamp 24 to grip the lower edge of the door upon which the hanger is mounted. The series of openings 23 in the upper end of the rod 22 affords vertical adjustment of the rod with respect to the arms 17 and 18 to which the rod is removably secured by passing the bolt 21 through any selected one of the slots or openings 23. In order to avoid chance marring of the door from the metal, wood or plastic parts just described, we preferably line inner surfaces of the cross-bar 11, the arms 17 and 18, and the rod 22 with fabric strips 27, or other cushioning material.

In addition to the foregoing elements, the improved door hanger of our present invention includes a retainer bar 28 which likewise can be fabricated from metal, plastic material or of hard wood, and which preferably is a relatively flat bar, as depicted in Figure 5 of the drawings. The bar 28 is provided with a pair of lugs 29 on its inner surface for enabling the hanging of the bar upon the arms 17 and 18 and thereby spreading such arms apart. The bar 28 is fixedly secured to the back of a shelf 31 or a cabinet 32, as illustrated in Figures 2 and 6, respectively, and the entire unit of bar and shelf, or bar and cabinet as the case may be, is hung upon the arms 17 and 18 by means of the lugs 29 carried on the back of the bar 28. A full length cabinet, as shown in Figure 6, can thus be supported on the hanger, or a smaller cabinet or even a shelf may similarly be mounted thereon.

As illustrated in Figures 3 to 5 inclusive, the elements of our improved door hanger are separable, and can be packaged compactly for easy shipping. The hanger is as readily taken down as it is installed upon a door. In order to mount the hanger in operative position on the inside of a door, such as a closet door, it is only necessary to lift the cross-bar 11, with its connected and supported arms 17 and 18 thereon, to the top of the door and slip the clamps 12 and 13 over the top edge of the door and release, thus supporting or suspending the cross-bar 11 in position. The screw-bolt 21 connecting the lower ends of the Y-arms 17 and 18 is faced outwardly from the door surface to avoid marring the same. Then attach the flat rod 22 to the screw-bolt 21 by slipping the screw-bolt through a selected opening 23 at the top of the rod 22, depending upon the height of the door, and slip the lower hook clamp 24 under the lower edge of the door. Thereafter, mount the shelf 31, or the cabinet 32 as the case may be, upon the arms 17 and 18 and, to effect this operation, fit the lugs 29 of the bar 28 which is attached to the back of the shelf

or cabinet, onto the arms 17 and 18, as clearly depicted in the dotted line showings of Figure 1 of the annexed drawings. The weight of the shelf or cabinet on the arms 17 and 18 will cause the arms to move apart or spread thus placing a tension on the arms and on the lower rod 22, and rigidly affixing the hanger in operative position. To dismantle the hanger, it is only necessary to lift the shelf or cabinet from the arms 17 and 18 and collapse the arms to relieve the tension on the rod 22 sufficiently to enable the removal of the rod from the bolt 21, as well as the removal of the clamp 24 at the bottom of the door. Thereafter, it is only necessary to lift the tension relieved cross-bar 11 from the top of the door.

It is clear from the foregoing that there is no need of screwing or nailing any of the elements of our improved hanger to the closet or other door upon which it may be mounted, in order rigidly to mount the same thereon. All of the elements of the hanger are light in weight and can be lifted readily by a house-wife and set in position. We have thus provided a convenient, easily mountable hanger unit for removable attachment to a closet or other door, making available additional facilities for storing or hanging wearing apparel of all types, or for the storing of a variety of different articles. Moreover, the improved door hanger is adaptable for use in suspending a short or a full length mirror on the inside of a door. As indicated in the drawings and as set out above, either a shelf, a small or a full length cabinet conveniently can be supported on the hanger and the hanger is readily taken down for use in other homes or apartments and need never be made a permanent fixture in any one place. The hanger, in addition, can be employed for suspending a locker, multiple shelving, containers or other articles and objects and is not necessarily to be limited merely to supporting a shelf or a cabinet. The improved hanger can readily be manufactured from inexpensive material, and can be shipped from place to place inexpensively in a compact shipping unit.

It is to be understood that the appended claims are to be accorded a range of equivalents commensurate in scope with the advance made over the prior art.

50 We claim:

1. A door hanger comprising a cross-bar having elongated slots therein, hook clamps on said cross-bar for suspending the same from the top edge of a door, a pair of arms pivotally connected together at their one ends and slidably mounted at their other ends on said cross-bar through the medium of said slots, a rod removably fastened to the connected ends of said arms, and a hook clamp on the opposite end of said rod for removably attaching the rod to the lower edge of a door.

2. A door hanger comprising a cross-bar having elongated slots therein, hook clamps on said cross-bar for suspending the same from the top edge of a door, a pair of arms pivotally connected together at their one ends and slidably mounted at their other ends on said cross-bar through the medium of said slots, a rod removably fastened to the connected ends of said arms; said rod having a series of openings therein near one end for enabling vertical adjustment of the rod with respect to said arms, and a hook clamp on the opposite end of said rod for removably attaching the rod to the lower edge of a door.

3. A door hanger comprising a cross-bar hav-

ing elongated slots therein, hook clamps for suspending said cross-bar from the top edge of a door, a pair of arms pivotally connected together

other ends on said cross-bar through the medium of said slots; said arms being adapted to assume an inverted triangle with respect to said cross-bar, a rod adjustably connected by means at one end to the connected ends of said arms, a hook clamp on the opposite end of said rod for removably attaching the same to the lower edge of a door, and means for placing a tension on said arms and said rod to install the hanger rigidly on a door.

4. A door hanger and article support comprising a cross-bar having elongated slots therein, hook clamps on said cross-bar for suspending the same from the top edge of a door, a pair of arms pivotally connected at their one ends and slidably mounted at their other ends on said cross-bar through the medium of said slots, and a bar removably connected to said arms; said bar being adapted removably to mount a cabinet on the hanger.

5. A door hanger and article support comprising a cross-bar having elongated slots therein, hook clamps on said cross-bar for suspending the same to the top edge of a door, a pair of arms pivotally connected at their one ends and slidably mounted at their other ends on said cross-bar through the medium of said slots, a shelf, a bar fastened to said shelf; said bar having means for removably mounting said shelf on said arms causing a spreading of the arms and the placing of

a tension thereon, a rod removably fastened to the connected ends of said arms, and a hook clamp on the opposite end of said rod for removably attaching the same to the lower edge of a

door.

6. A door hanger and article support as defined in claim 5, and including means for vertically adjusting said rod with respect to said arms.

7. A door hanger as defined in claim 1, and 10 a bar, and means on said bar for removably mounting a cabinet on the hanger.

8. A door hanger as defined in claim 1, and having means to removably mount a shelf on said arms.
